UNITED STATES PATENT OFFICE

BOHUMIL POLÁK, OF PRAGUE, CZECHOSLOVAKIA

DEVICE FOR OPENING CONTAINERS SUCH AS BOXES, TINS, OR THE LIKE

Application filed January 17, 1928, Serial No. 247,392, and in Germany December 12, 1927.

This invention is concerned with improvements in or modifications of the devices for opening containers such as boxes, tins or the like of the type claimed in the specification 5 of my Patent No. 1,734,877, Ser. No. 150,311.

According to the present invention the opener consists of a sheet metal strip having a flat centre portion with a pivot opening surrounded by a pressed up hollow rib and a 10 wing portion or portions extending longitudinally of the opener, standing up from the centre portion and preferably formed with convenient gripping means such as a spherical end or ends.

15 The peripheral rib surrounding the pivot opening may be stiffened by grooves formed therein on either side of the longitudinal axis of the opener, and its edge is preferably bent up at right angles at all four rounded corners 20 to form sharp edges to facilitate engagement under the lid rim.

Further to ensure said engagement under the lid the lower portion of the container may be furnished with a depression or flat upon 25 which the opener is pivoted with the aid of the usual rivet.

One embodiment of the invention is illustrated by way of example in the accompanying drawing in which:

30 Fig. 1 is a plan view of an opener,

Fig. 2 an elevational view partly in section on the line 2-2 in Fig. 1,

Fig. 3 a cross section on the line 3-3 of Fig. 1,

35 Fig. 4 a similar view of the opener in position upon the container and

Fig. 5 a similar view of the container with the opener and lid removed.

The opener, which is made of thin sheet 40 metal, consists of a metal strip the plain middle portion 1 of which has an opening 2 for the rivet whereby said opener is pivotally secured to the wall 8 of the sheet metal container. The opener is furnished with a 45 pressed up hollow rib 3, surrounding the mid-

dle portion 1, the outside edge of which is bent up horizontally at all four rounded corners of its shape in plan, thus forming sharply pointed edges 4. The peripheral rib 3 is stiffened on either side of the longitudinal axis of the opener by radial grooves 5. The portions of the hollow rib 3 enclosed between the pairs of grooves 5 are formed with extensions 6 which are located in the longitudinal axis of the opener and, in longitudinal section (as illustrated in Fig. 2), are bent out in a gentle curve so that they project from the base surface of the middle portion 1 in the same direction as the peripheral rib 3 and have an approximately semi-circular cross-section. The outside ends of the extensions 6 are shaped as hollow spheres 7 which provide a convenient means for handling the opener.

The opener is pivotally secured by means of a rivet to the lower or main portion of the container 8 towards the upper edge thereof and preferably upon a flat or depression thereon. On twisting the opener the sharp edges 4 first of all engage under the rim of the container lid 9 and upon further rotation the 70 rim 9 of the lid comes to bear on the wall of the peripheral rib 3 and may thus be removed from the lower portion of the container.

Having now particularly described and 75 ascertained the nature of my said invention and in what manner the same is to be performed, I declare that what I claim is:

1. A lid raising cam for opening a receptacle of that type in which the lid has a side 80 wall telescoping frictionally over the side wall of the body of the receptacle, comprising, a stamped sheet metal member formed with the following structural elements, a center portion having a pivot opening, an 85 oblong rib surrounding the center portion and elevated above said center portion and convex considered from that side which is adapted to lie away from the receptacle, a flange 90 extending from said rib at least from those

portions thereof at the end of the diagonals or the oblong shape defined by said ribs said flange lying substantially in the plane of the center portion, and a handle extending in a 5 longitudinal direction outwardly from said rib.

2. A lid raising cam as claimed in claim 1, said rib being stiffened by grooves formed therein on either side of the longitudinal medium line of said cam.

10 In testimony whereof I have signed my name to this specification.

BOHUMIL POLÁK.
